UNITED STATES PATENT OFFICE.

IRA F. GORHAM, OF ENSLEY, ALABAMA.

PERMUTATION-LOCK.

1,194,286.

Specification of Letters Patent.

Patented Aug. 8, 1916.

Application filed September 15, 1914. Serial No. 861,864.

To all whom it may concern:

Be it known that I, IRA F. GORHAM, a citizen of the United States, residing at Ensley, in the county of Jefferson and State of Alabama, have invented new and useful Improvements in Permutation-Locks, of which the following is a specification.

The invention relates to locks, and more particularly to the class of permutation car door locks.

The primary object of the invention is the provision of a permutation lock wherein the same is operated through the medium of gears which are controlled by permutation knobs so that the lock can be manipulated only by a person having knowledge of the combination, thereby avoiding the possibility of fraudulent entry to the car or other inclosure.

Another object of the invention is the provision of a permutation lock of this character wherein the permutation mechanism can be changed or altered so as to change the combination for the working of the lock, thereby rendering the same safe and practically burglar-proof.

A further object of the invention is the provision of a permutation lock of this character wherein the permutation mechanism will have to be accurately adjusted before the locking mechanism will operate for permitting the opening of a door.

A still further object of the invention is the provision of a permutation lock of this character which is simple in construction, thoroughly reliable and efficient in its purpose, strong, durable and inexpensive of manufacture.

Other objects will be in part obvious and in part hereinafter set forth.

The invention accordingly consists in the features of construction, combination of elements and arrangement of parts which will be exemplified in the construction herein-after set forth, and the scope of the application of which will be indicated in the claims hereunto appended.

In the accompanying drawings: Figure 1 is a fragmentary front elevation of a freight car door frame and door, with a lock constructed in accordance with the invention applied; Fig. 2 is a fragmentary elevation of the lock looking toward the inner side of the door frame and door; Fig. 3 is an en-

larged sectional view taken on the line 3—3 of Fig. 1; Fig. 4 is a view taken approximately on the line 4—4 of Fig. 1; Fig. 5 is a side elevation of the lock with one facing plate removed; Fig. 6 is a fragmentary vertical sectional view showing the lock engaged with the keeper for securing the door closed; Fig. 7 is a sectional view on the line 7—7 of Fig. 3. Fig. 8 is a fragmentary vertical transverse sectional view through the handle showing in detail the car seal and handle lock; Fig. 9 is a perspective view of one of the gears; and Fig. 10 is a fragmentary detail plan view of the slide.

Similar reference characters indicate corresponding parts throughout the several views of the drawings.

Referring to the drawings in detail, A designates a portion of the door frame in the side wall of a freight car or the like, and B a portion of the sliding door which is mounted for opening and closing movement as usual. Mounted on the inner face of the door frame at one side thereof is a keeper C, while mounted on the door B is the permutation lock D, both the keeper and the lock being hereinafter fully described.

Secured to the outer face of the door B is a rectangular shaped escutcheon or face plate 10, preferably made from metal, while disposed against the inner face of the said door is a base plate 11 supporting the lock D, which comprises a slide 12 formed with a series of spaced large and small circular openings 13 and 14 respectively, arranged alternately with respect to each other centrally of the slide. Formed centrally of the slide 12, longitudinally thereof, are straight slots 15 which connect the openings 13 and 14 with each other, and this slide is disposed between spaced parallel walls 16 and 16' of a housing 17 which is secured in place by means of bolts 17' passed through spacer collars 18 interposed between the rear walls 16' of the housing and the base plate 11, the bolts 17' being also passed through the door B and both the escutcheon or face plate 10 and base plate 11, as shown. Journaled transversely of the housing 17 in the front and rear walls 16 and 16' are spaced stud axles 19, each supporting thereon a pair of juxtapositioned gears 20 and 20' each formed with a hub 21 provided with diametrically opposed flat or straight faces 22,

and these hubs 21 are of a size corresponding to the small openings 14 so that when the same register therewith the gears 20 and 20' are free for rotation, whereby the 5 straight or flat faces 22 on the hubs 21 can be brought into a plane with the planes of the edges of the straight slots 15 to free the slide 12 for movement in contra-distinction to the locking thereof when the hubs 21 are 10 in the openings 14 and have been turned to dispose the flat faces 22 thereof out of the plane of the edges of the straight slots 15 in the slide.

Arranged at one side of each pair of gears 15 20 and 20' is a pair of operating gears 23 and 23' which mesh therewith, the gears 23 being supported upon the squared portions 24 of turning axles 24', while the gears 23' are mounted upon squared portions of 20 sleeves 25 for sliding movement thereon, and to rotate therewith, the sleeves surrounding the axles 24' which, together with the sleeves, extend through the door B and plates 10 and 11, the gears 23 and 23' being formed 25 with circular hubs 26 which are journaled in the walls of the housing 17, while the axles 24' and sleeves 25 extend through the larger openings 13 in the slide 12, as shown.

Interposed between the gears 23 and 23' 30 and surrounding the axles 24' are compression springs 27 which serve to normally hold the gears in meshing engagement with the gears 20 and 20' so that on the rotation of the said gears 23 and 23' similar movement 35 will be imparted to the gears 20 and 20' for the working of the lock is a manner presently described.

Fixed to the outer ends of the sleeves 25 are turning knobs 28 and likewise fixed to 40 the outer ends of the axles 24' are turning knobs 29, the said knobs 28 and 29 being formed with dial surfaces 30 on which are arranged series of numerals and letters employed to indicate certain combinations to 45 be worked for permitting the locking and unlocking of the lock.

Pivots supported on the base plate 11 is a series of levers 31, each provided with a fork 32 at one end which works against 50 the hub 26 of each gear 23', and these levers permit the disengagement of the gears 23' with the gears 20' so that the knobs 28 and 29 can be turned for changing or altering the combination to permit the working of 55 the lock, the combination being effected by the numerals and letters on the respective dial faces by the matching of certain combinations of letters or numerals in the ordinary well known manner.

60 Fixed to one end of the slide 12 is a substantially sphere shaped locking head 34 which coöperates with pivotally supported outwardly bowed clamping jaws 35, the pivots 36 therefor being mounted in the door 65 B and adapted to engage stop pins 37

mounted in a frame 38 which constitutes the keeper C. The head 34 is formed with cam surfaces 39 which engage the concave portions of the jaws 35 to automatically move the same to clamping or unclamping position. Spaced from the end of the slide 12 opposite the head 34 thereon is a turning stem 40 which is passed through the door B and is journaled in the respective face and base plates 10 and 11 thereon, the stem being 70 formed at its outer end with a handle 42, while its inner end has fixed thereto a crank 43 pivotally connected to a link 44 which is also pivoted to the end adjacent thereto of the slide 12 and on the unlocking of the said 75 slide upon turning the stem 40 it can be shifted to locking or unlocking position relative to the keeper C on the door frame.

At one side of the stem 40 and mounted exteriorly of the door B is a stationary keeper 45 with which coöperates the handle 42 for the locking thereof. The handle 42 is formed in its free end with a slot 46 providing a clearance for a beveled nose 46' on the keeper 45, and rearwardly of this 90 nose 46' on said keeper is a notch 47, while formed in the handle 42 and intersecting the slot 46 is a socket 48 in which is adapted to be placed a disk constituting a seal which, on the swinging of the handle in one direction, is moved upwardly in the slot 48 by the nose 46' and thereafter drops into the notch 47, thus locking the handle against turning movement. In the turning of the handle 42 the disk or seal is broken, which 95 permits the free turning of the handle.

When the slide 12 is in position for locking the door the small openings 14 will be in registration with the hubs of the gears 20 and 20' which have been turned on operating 100 the knobs 28 and 29 so that the flat surfaces 22 are out of alignment or in the plane of the edges of the straight slots 15, thereby locking the said slide 12 against movement. Now when the knobs 28 and 29 have been 105 turned for the matching of certain letters and numerals selected for the combination to effect the unlocking of the lock by an operator the gears 23 and 23' will rotate the gears 20 and 20' so as to turn the straight 110 portions or faces 22 of the hubs of said latter gears into alignment with the slots 15 in the slide 12 so that the latter is free for movement when manipulating the handle 42 to 115 unlock the door.

On moving any one of the levers 31 the gear 23' controlled thereby can be thrown out of mesh with the gear 20' adjacent thereto and thereafter either knob 28 and 29 can be turned for altering the combination 120 for the locking or unlocking of the lock.

From the foregoing description, taken in connection with the accompanying drawings, the construction and manner of operation of the lock will be readily apparent, and 125 130

a more extended explanation has, therefore, been omitted.

Having thus described my invention, I claim:

5. 1. In a lock of the class described, a slide having spaced circular large and small openings and also straight slots therebetween and communicating therewith, a plurality of pairs of gears arranged in series independent of each other, the gears of each pair meshing with each other, alternate gears of one series being movable into the larger circular openings in the slide, hubs on certain gears of both series engageable in the smaller openings and having straight surfaces in correspondence with the slots to be received therein, and mechanism for rotating alternate gears of each series.
2. In a lock of the class described, a slide having spaced circular large and small openings and also straight slots therebetween and communicating therewith, a plurality of pairs of gears arranged in series independent of each other, the gears of each pair meshing with each other, alternate gears of one series being movable into the larger circular openings in the slide, hubs on certain gears of both series engageable in the smaller openings and having straight surfaces in correspondence with the slots to be received therein, mechanism for rotating alternate gears of each series, and permutation dials included in said mechanism.
3. In a lock of the class described, a slide having spaced circular large and small openings and also straight slots therebetween and communicating therewith, a plurality of pairs of gears arranged in series independent of each other, the gears of each pair meshing with each other, alternate gears of one series being movable into the larger circular openings in the slide, hubs on certain gears of both series engageable in the smaller openings and having straight surfaces in correspondence with the slots to be received therein, mechanism for rotating alternate gears of each series, permutation dials included in said mechanism, and means for shifting certain of the gears with relation to the other gears to vary the combination of the permutation dials.
4. In a lock of the class described, a slide having spaced circular large and small openings and also straight slots therebetween and communicating therewith, a plurality of pairs of gears arranged in series independent of each other, the gears of each pair meshing with each other, alternate gears of one series being movable into the larger circular openings in the slide, hubs on certain gears of both series engageable in the smaller openings and having straight surfaces in correspondence with the slots to be received therein, mechanism for rotating alternate gears of each series, permutation dials included in said mechanism, means for shifting certain of the gears with relation to the other gears to vary the combination of the permutation dials, manually operable means for shifting the slide when released by the hubs, a keeper, means on the slide for engagement in the keeper, and means acting upon the gears for normally sustaining the same in meshing engagement with each other.
5. In a lock of the class described, a slide having spaced circular large and small openings and also straight slots therebetween and communicating therewith, a plurality of pairs of gears arranged in series independent of each other, the gears of each pair meshing with each other, alternate hubs of one series being movable into the larger circular openings in the slide, hubs on certain gears of both series engageable in the smaller openings and having straight surfaces in correspondence with the slots to be received therein, mechanism for rotating alternate gears of each series, permutation dials included in said mechanism, means for shifting certain of the gears with relation to the other gears to vary the combination of the permutation dials, manually operable means for shifting the slide when released by the hubs, a keeper, and means on the slide for engagement in the keeper.
6. In a lock of the class described, a slide having spaced circular large and small openings and also straight slots therebetween and communicating therewith, a plurality of pairs of gears arranged in series independent of each other, the gears of each pair meshing with each other, alternate gears of one series being movable into the larger circular openings in the slide, hubs on certain gears of both series engageable in the smaller openings and having straight surfaces in correspondence with the slots to be received therein, mechanism for rotating alternate gears of each series, permutation dials included in said mechanism, means for shifting certain of the gears with relation to the other gears to vary the combination of the permutation dials, manually operable means for shifting the slide when released by the hubs, a keeper, means on the slide for engagement in the keeper, and means acting upon the gears for normally sustaining the same in meshing engagement with each other.
7. In a lock of the class described, a slide having spaced circular large and small openings and also straight slots therebetween and communicating therewith, a plurality of pairs of gears arranged in series independent of each other, the gears of each pair meshing with each other, alternate gears of one series being movable into the larger circular openings in the slide, hubs on certain gears of both series engageable in the smaller openings and having straight surfaces in correspondence with the slots to be received therein, mechanism for rotating alternate gears of each series, permutation dials included in said mechanism, means for shifting certain of the gears with relation to the other gears to vary the combination of the permutation dials, manually operable means for shifting the slide when released by the hubs, a keeper, and means on the slide for engagement in the keeper.

dials included in said mechanism, means for shifting certain of the gears with relation to the other gears to vary the combination of the permutation dials, manually operable means for shifting the slide when released by the hubs, a keeper, means on the slide for engagement in the keeper, means acting upon the gears for normally sustaining the same in meshing engagement

with each other, and a keeper for coöperation with the manually operable means.

In testimony whereof I affix my signature in presence of two witnesses.

IRA F. GORHAM.
